UNITED STATES PATENT OFFICE.

JOSEPH H. LYNCH, OF ASBURY PARK, NEW JERSEY.

METHOD AND MACHINE FOR APPLYING LAUNDRY TAGS.

Application filed January 24, 1925. Serial No. 4,528.

This invention relates to a method and machine for attaching for identification, metal tags or tokens to pieces of cloth that are to be laundered, and to a tag carrier or token tally to be used in connection therewith.

The object of the invention is to provide a safe and convenient means of handling the tags to save labor in applying the tags to the cloth, economize on the time required for doing the same, and insure a more secure attachment of the tag to the cloth. Heretofore, a preferred method has been to have the tags supplied from a pile located in a reservoir attached to the machine, the mechanism of the machine being employed to take one tag at a time from the reservoir, apply it to the cloth and secure it thereon. Such machines have inherent objections, due to the difficulty of handling with mechanism, tags which are of necessity lacking in simplicity of contour. In my present invention I obviate the necessity of using a pile of tags by assembling the tags on a tag assembly which may take the form of a flexible belt, the belt or other form of tag assembly being provided with a separate holder for each tag and being adapted to be applied to the machine and to bring the tags to the applying mechanism on the machine one after the other as the tag assembly is fed forward in the machine.

The invention will be better understood by a detailed description of an embodiment illustrated in the accompanying drawings, in which

Figure 1 is a side elevation of the complete machine.

Figure 2 is a vertical section of the upper part of the machine on the line 2—2 of Figure 1.

Figure 3 is a detail section on the line 3—3 of Figure 6.

Figure 4 is a longitudinal vertical section of the complete machine.

Figure 5 is a side view and partial section of the upper part of the machine viewed from the reverse direction of Figure 4.

Figure 6 is a plan view.

Figure 7 is a horizontal section of the base of the machine on the line 7—7 of Figure 4.

Figure 8 is a vertical section on the line 8—8 of Figure 7.

Figure 9 is a side elevation of a detail of the crank mechanism.

Figure 10 is a top view of the tag.

Figure 11 is a side view of the tag.

Figure 12 is a bottom view of the tag; and

Figure 13 is a perspective view of one tag holder.

Referring to the drawings, the machine comprises a hollow frame 1 having at its lower portion a bracket 2 supporting an electric motor 3. The motor drives through a belt 4 a shaft 5 having a pinion 6 with an elongated face with which is meshed a gear 7 keyed to a counter shaft 8. The shaft 8 has also secured or fastened to it two bevel pinions 9. The shaft 8 is capable of longitudinal motion in its bearings 10 whereby either one of the pinions 9 may be caused to enmesh with bevel wheel 11, while gears 6 and 7 remain enmeshed. The bevel wheel 11 is secured to a crank shaft 12 on the other end of which is a crank disk 13 having a crank pin 14 adapted to travel in a slot 15 of a sliding cross-head 16, by means of which a vertical rod 17 may be made to reciprocate vertically. The shaft 8 is shifted back and forth to cause either one or the other of the bevel pinions 9 to engage with the bevel wheel 11 by means of a lever 18 engaging with a collar 19 at the end of the shaft. The lever 18 is secured to a vertical shaft 20, the upper and lower ends of which are supported by brackets 21 on the frame and has a crank arm 22 engaging with the arm 23 of a hand lever 24 pivoted in the frame at 25. The operator may by this lever 24 cause one or the other of the pinions to engage with the bevel wheel which will then rotate. However, after traversing approximately 180° a pin 26 on the bevel wheel engaging with a cam 27 pivoted at 28, throws out of engagement the pinion that is driving the wheel by means of a pin 29 engaging in a slot on the hub of the pinion. The use of this device will be described later. The rod 17 has a bracket arm 30, a pin 31 on the end of which engages with a slot in the arm 32 of a bell crank lever pivoted at 33 on the frame, the other arm of the lever 34 having a pin in slotted engagement with a rocker arm 35 pivoted on a shaft 36 which is journalled in the frame at 37. A spring actuated pawl 38 pivoted

also on the rocker arm 35 makes a step by step engagement with a ratchet wheel 39 which is secured to the shaft 36. The ratchet wheel 39 has six teeth for engagement with the pawl 38 and therefore moves one-sixth of a turn for each back and forth motion of the bell crank 34. The pawl 40 held by spring 41 against the ratchet, prevents any retrograde motion on the part 5 of the ratchet wheel. On the shaft 36 is mounted a hexagonally faced pulley 42. A clutch 43 having a handle 44 is capable of sliding endwise on the shaft and when held toward its inner position by spring 45, 10 causes pins 46 to engage the clutch 43 with the hub of the pulley 42, the clutch being driven positively by means of pin 47 secured to the shaft. When the clutch is in engagement, each forward motion of the 15 rocker arm 34 to the right in Figure 4, causes the six-sided pulley to move 60° and at the end of its stroke leave one of the flat sides of the hexagon flush with the table surface 48 of the frame of the machine. 20 On the backward stroke, however, of the rocker arm 34 no motion is imparted to the hexagonal pulley and it is during this period of rest that the mechanism for applying the tags comes into operation. The 25 tags are assembled on belts, tag carriers or tag assemblies, one of which is shown at 49 (see Figures 1 and 5) there being a series of holders 50 permanently secured to the belt, for that purpose, the holders being spaced apart a distance equal to the distance from the center of one hexagonal surface to the next. Each belt or carrier is devoted to one particular identification number and only tags having the proper identification number on them are assembled 30 on any one belt. The carrier thus becomes a tally for the tags or tokens belonging to it, showing by the number of tags absent from it or the number remaining on it, the number of that particular group that are being used. Each holder on the carrier is adapted to receive one tag, and the belt, with the tags assembled in the holders, 35 is introduced into the machine by being slipped onto the pulley where inwardly protruding lugs 51 of the tag holders (see Figures 2 and 13) will engage in slots 52, of which there are two in the middle of each of the hexagonal sides of the pulley 42 while longitudinal crimps 51' fit into longitudinal grooves in the middle of the pulley faces. In order to insure that the pulley 40 will remain steady during the stamping operation, a spring actuated lever 53 (see Figure 5) is made to impinge by means of a roller 54 against one edge of the lower side of the pulley to hold the same in such a way that ratchet wheel 39 will be firmly pressed against pawl 40. The mechanism for applying the tags to the cloth consists 45 of a foot 55 which is pivoted at 56 on an arm 57, which in turn is supported adjustably on the end of a lever 58. 59 are springs for providing a certain amount of yielding on the part of the foot 55 and adjusting screw 60 may be used for varying the elevation of the toe of the foot 55. The lever 58 has a combined up and down and forward and backward motion similar to the feed of a sewing machine. This motion is 50 accomplished by the following mechanism. The rear of the lever 58 has a slot 61 in which a fulcrum pin 62 plays, there being a plunger 63 in a connecting rod 64 pivoted at its lower end to the frame and containing a spring 65 which tends to keep the heel of the lever 58 in its upper position at the upper end of the slot 61. At 63 is shown a crank pin for operating the lever 58. The pin is carried by a shaft 67 journalled in the frame at 68 and on the other end of the shaft a pinion 69 is secured. Meshing with this pinion is a gear of twice its diameter 70 which is mounted loosely 60 on a shaft 71. Secured to the shaft 71 is a double toothed ratchet 72 engaging with a pawl 73 pivoted on the side of the gear 70 and held in spring contact with the ratchet 72 by spring 74. The shaft 71 has two pinions 75 secured to it, which mesh with the two rack portions 76 (see Figure 4) that are secured adjustably by screw member 77 to the vertically reciprocating rod 17. The diameter of the pinions 75 is so proportioned to the stroke of the rod 17 that upon a complete down stroke of the latter the pinions will make one-half of a revolution and will, consequently, through ratchet 72 and pawl 73, cause the gear 70 to make one-half a revolution, which will result in one complete revolution of the pinion 69 and the crank 66. During the return stroke of the rod 17, the pawl 73 will slip backward over the ratchet 72 and no motion of the crank will take place, the crank being held at this time in the steady position of rest, by means of a pawl 78 (see Figure 4) acting against a one toothed ratchet disk 79 on the crank shaft, the pawl being held to its position by 70 spring-pressed pin 80. It will be seen, therefore, that when the reciprocating rod 17 makes its down stroke, which corresponds to the idle period of the belt operating mechanism, the crank pin 66 will carry the foot 55 first downward, then forward, then upward and then backward. In performing these motions, the foot 55 will be brought to bear down upon the top of the tag, which is then resting on the top of the hexagonal pulley and engaging behind a boss 81 provided on the top of each tag (see Figures 10 and 11) will first press the upper part of the hinged tag downward, thus closing the same upon the goods, 110 115 120 125 130

and then by its forward motion pushing it against the boss 81 to cause the locking slide 82 to move forward until the lips 83 of the slide engage under the locking flanges 84 that form part of the lower member of the tag. When the foot 55 has so closed the tag onto the cloth, it can, of course, not descend any further and to accommodate the further movement of the crank 66 is the object of the slot 61 and yielding spring abutment 63 at the heel of the lever 58. After the tag has been thus applied the foot continues its motion and rises free of the tag. The tag consists of an upper and lower member spring-hinged together at one end and the locking slide is mounted slidably upon the upper member. Each tag has stamped or imprinted upon it an identification number. To hold the tag in position on the belt, the tag holders have a bent-over portion 85 (see Figure 5) which engages with a hole 86 in the tag. This hole is in both the slide and the upper and lower members of the tag and the portion 85 of the holder that is bent over to hold the tag is rounded so that the tag may be easily slipped in under it and also that the sliding member may be slipped out from under it when the tag is fastened to the goods. The tag itself is securely held in place both sidewise and endwise by lips 87 on the tag holders (see Figure 13) the end lip serving also as an abutment to hold the tag against the endwise thrust of the presser foot 55.

In order to insure that the edge of the cloth will be inserted just the right distance in between the jaws of the tag, I provide stops 88 on each side of the presser foot 55, the forward end of these stops being curved upward to facilitate the insertion of the edge of the cloth and the mid-length of the stops having an edge formed by the foot of the stop, said edge being exactly in line with the center of the pulley and, therefore, corresponding to the inner limit of the gripping part of the tag. To facilitate the introduction and withdrawal of the tag holding belt part of one side of the table, as shown at 89, is made of a separate piece hinged as shown at 90 (see Figures 5 and 6). This part of the table can thus be swung out of the way to put on or take off a belt. A rod or bracket 91 extending from the reciprocating part 30 serves to actuate a counter mechanism 92 to register the number of articles tagged.

The operation of the machine is as follows:

It will be understood that there will be furnished with each machine a number of the tag carriers, each carrier as well as the tags carried by it having one identification number. There will then be selected one belt for each batch of laundry requiring

a given identification having assembled on it laundry tags, one tag being held by each holder on the belt. Such a belt being slipped over the hexagonal pulley, the hinged portion 89 being swung for that purpose, and an edge of the cloth being slipped in between the jaws of the tag until the said edge rests against the stops 88, the operator, pressing on lever 24 with his finger, will throw one of the pinions 9 into engagement with the bevel wheel 11 whereupon the presser foot 55 will be caused to move down onto the tag, pressing the two jaws of the same together and then by a forward movement, the said presser foot engaging with the boss 81 on the tag, will push the locking slide forward until the lips 83 of the same engages under the flanges 84 of the lower jaw, thus securely locking the tag on the cloth. The tag is prevented from moving forward under this pushing action by being held against stop 87 of the tag holder. The presser foot then moves up out of the way and as the spring has now been taken out of the tag, the said spring action of the hinge of the tag having thus far securely held the tag in position on the tag holder by virtue of the upward pressure of the upper member of the tag against the overhanging arm 85 of the tag holder, the cloth may be freely withdrawn with its tag. When the presser foot has thus been lifted out of the way, the pinion 9 that was in engagement with the bevel wheel 11 will be thrown out of engagement by the pin 26 striking the cam 27. The operator may then, by moving the lever 24 in the opposite direction, cause the other pinion to engage with the bevel wheel 11. It should be noticed here that should the operator try to repeat the former operation at this point to re-engage the pinion that was just forced out of operation, he will be unable to accomplish it because the bevel wheel 11 having come to rest with the pin 26 against the cam 27, the pinion that was in engagement cannot again be put into mesh. Moving the lever in the opposite direction, however, brings the other pinion 9 into engagement with the bevel wheel 11 and thus causes a reverse movement of the connecting rod 17, the rod in this case moving upward instead of downward, the result of which is to turn the hexagonal pulley 60° backward, thus bringing another tag into operative position beneath the presser foot. When it has reached this position, the pulley will be firmly held through the combined action of spring pawl 53 and pawl 40. At the end of the upward stroke, the bevel wheels are again disengaged by pin 26 striking the other cam 27, and again the operator is prevented from re-engaging the gears just disengaged. The machine is then ready for

another piece of goods.

When all the articles of a given identification have been thus tagged, the belt 49 may be removed and set aside and contains itself a record of the number of pieces that have gone into the laundry with this identification. When the tags are to be removed from the goods, they are easily slipped off by hand, by sliding back the locking plate 82 and they may be at the same time replaced one by one in their proper belt. A clutch 43 is provided for the purpose of enabling the operator to disconnect the hexagonal pulley from the rest of the mechanism when it may be moved back or forth one or more steps in case the right part of the carrier belt is not presented to the presser foot.

While I have shown a particular embodiment of my invention in what has proved to be a successful method and machine, I do not wish to be limited in my claims to the specific devices herein illustrated and described. In the tag holding belt I have provided a token-tally, which keeps a record of the articles, and while I have shown this in the form of a belt to be operated over a polygonal pulley, it may take other forms and be used in other ways.

I claim:

1. The method of applying tags to goods which comprises, assembling the tags on individual tag holders on a tag carrier, applying the goods to be identified to the tags while the tags are on the holders, clamping the tags on the goods and then removing the goods with the tags from the tag holders, whereby the tag carrier becomes a tally of the number of tags used and a keeper for the tags when not in use.

2. In a system for utilizing identification tags for different batches of goods, the method comprising assembling the tags on individual tag holders on a carrier, placing the carrier in a tag applying machine, causing the machine to apply the goods of one batch to the tags in seriatim, removing the carrier from the machine, and subsequently removing the tags from the goods and replacing them on the carrier.

3. The method of applying tags to goods which comprises, assembling the tags on individual tag holders on flexible carriers, applying the tag carriers one at a time to a tag affixing machine, moving the tag carrier step by step to bring one holder with its tag to a tag affixing point applying the goods to be identified to the tags on the holder, and clamping the tags on the goods by an intermittent operation alternating with the step by step carrier feeding operation.

4. The combination with a tag applying machine of a tag carrier having a series of tag holders secured at regular intervals thereon, means on the machine for feeding the carrier one tag holder at a time, means

acting alternately to the feeding means to close the tags and lock the same, and means on the tag holder for holding the tag from displacement on the holder during the closing of the tag.

5. The combination with a tag applying machine of a tag carrier having a series of tag holders secured at regular intervals thereon, means on the machine for feeding the carrier one tag holder at a time, means acting alternately to the feeding means to close the tags and lock the same, means for holding the tag holder from displacement on the feeding means, and means on the tag holder for holding the tag from displacement on the holder during the closing of the tag.

6. In a machine for applying identification tags to goods, the combination comprising a power means, a tag carrier having secured at regular intervals a series of tag holders, means for feeding the carrier intermittently, means acting alternately to said feeding means for applying tags held in the holder to the goods, and manual means for alternately engaging the feeding and applying means with the power means.

7. In a machine for applying identification tags to goods, the combination comprising motive power means, means for feeding intermittently a series of tags, means acting alternately to said feeding means for applying the tags to the goods, means manually controlled for connecting alternately the feeding and applying means to the motive power, and automatic means for disconnecting such connecting means.

8. In a machine for applying identification tags to goods, the combination comprising motive power means, means for feeding intermittently a series of tags, means acting alternately to said feeding means for applying the tags to the goods, means manually controlled for connecting alternately the feeding and applying means to the motive power, automatic means for disconnecting such connecting means, and other means for preventing the reconnecting of the means last disconnected.

9. The combination with a tag applying machine of a flexible tag carrier having a series of tag holders secured to it at regular intervals, a polygonal pulley for supporting and feeding the carrier, the flat faces of the pulley corresponding in length with the said intervals, means for turning the pulley to bring one face at a time to a tag applying point, and means acting alternately to said turning means for closing the tag located at the tag applying point.

10. The combination with a tag applying machine of a flexible tag carrier having a series of tag holders secured to it at regular intervals, a polygonal pulley for supporting and feeding the carrier, the flat faces of

the pulley corresponding in length with the said intervals, means for turning the pulley to bring one face at a time to a tag applying point, means for holding the pulley fixed when so turned, and means acting alternately to said turning means for closing the tag located at the tag applying point.

11. The combination with a tag applying machine of a flexible tag carrier having a series of tag holders secured to it at regular intervals, a polygonal pulley for supporting and feeding the carrier, the flat faces of the pulley corresponding in length with the said intervals, means for holding the tag holders in fixed position on the pulley, means for turning the pulley to bring one face at a time to a tag applying point, means for holding the pulley fixed when so turned, and means acting alternately to said turning means for closing the tag located at the tag applying point.

12. The combination with a tag applying machine of a flexible tag carrier having a series of tag holders secured to it at regular intervals, a polygonal pulley for supporting and feeding the carrier, the flat faces of the pulley corresponding in length with the said intervals, means for holding the tag holders in fixed position both laterally and longitudinally on the pulley, means for turning the pulley to bring one face at a time to a tag applying point, means for holding the pulley fixed when so turned, and means acting alternately to said turning means for

closing the tag located at the tag applying point.

13. The combination with a tag applying machine of a flexible tag carrier having a series of tag holders secured to it at regular intervals, a polygonal pulley for supporting and feeding the carrier, the flat faces of the pulley corresponding in length with the said intervals, means for turning the pulley to bring one face at a time to a tag applying point, and pawl and ratchet driving means for alternately actuating the feeding pulley and the applying means.

14. A portable tag carrier made of a flexible band and having a series of tag holders permanently secured thereto at regular intervals, and means on each holder for resiliently holding the tags in place on the holder.

15. A portable flexible tag carrier having a series of tag holders permanently secured thereto at regular intervals, means on each holder for resiliently holding the tags against the holder, and means also on each holder for preventing longitudinal displacement.

16. A portable flexible tag carrier having a series of tag holders permanently secured thereto at regular intervals, with means on the carrier on the reverse side from the tag holders for positively engaging said carrier with a propelling mechanism.

JOSEPH H. LYNCH.
